UNITED STATES PATENT OFFICE.

ALFRED JAMES WAINMAN, OF NEW HARTFORD, ASSIGNOR TO MOHAWK VALLEY SCOTCH CAP FACTORY, OF UTICA, NEW YORK.

NARROWING-COMB FOR KNITTING-MACHINES.

SPECIFICATION forming part of Letters Patent No. 317,598, dated May 12, 1885.

Application filed April 22, 1884. (No model.)

To all whom it may concern:

Be it known that I, ALFRED JAMES WAINMAN, of New Hartford, in the county of Oneida and State of New York, have invented certain new and useful Improvements in Narrowing-Combs for Knitting-Machines; and I do hereby declare the following to be a full, clear, and exact description of the invention, such as will enable others skilled in the art to which it applies to make and use the same.

My invention relates to knitting-machines, and has particular reference to devices for narrowing the fabric.

Hitherto the ticklers have been mounted on a bar and divided into two series, the ticklers of each series being connected by links for the purpose of permitting them to separate slightly, and the two series connected to a lever, whereby they are moved simultaneously.

The object of my invention is to provide a narrowing-comb which shall be well adapted to the purposes of constructing a seamless cap or other article wherein the narrowing or widening is required to be distributed throughout the entire circuit of the fabric, and which shall be simple in its construction, rapid in its operation, durable, and inexpensive.

With these ends in view my invention consists in certain features of construction and combinations of parts, as will be hereinafter fully described, and pointed out in the claims.

In the accompanying drawings, Figure 1 is a view of my improved narrowing-comb in perspective. Fig. 2 is a plan view with guard removed, and Fig. 3 shows enlarged views of the links connected together and detached and a transverse sectional view through the bar and point-plate.

A represents a flat metal bar rigidly secured to the ends of two flat metal arms, B. The arms B are secured firmly to a curved metal sheet, C, which is bent hook-shaped in cross-section at the rear, as shown at c, and at the front terminates in a curved guard, c', which overlaps and covers and protects the spring and rod. The sliding plates D, with one or more perforated points, d, are made uniform in size, and are preferably constructed of thin sheet-steel, the plate and its point or points being formed integral. The plates D lie closely in contact with the under side of the flat

bar A, and are held in position by shouldered plates E, secured to the upper surfaces of the plates D, adapted to embrace the flat bar A as snugly as is consistent with an easy-sliding motion thereon. The plates E are preferably secured to the plates D by rivets.

To the upper surfaces of the several plates E the sliding link-sections f and f' are successively secured, interlock, and limit the distance to which any two successive plates D may be separated. The links are preferably constructed as shown in the drawings, and have bearings on each other a sufficient distance apart to allow the plates to slide on the bar A without having a tendency to bind. The link-section f consists of a flat metal strip provided on one of its edges with the upwardly-extending lugs or ears g, formed integral therewith, and on the other edge with the arms g', having approaching ends also formed integral with the strip. The link-section f' consists of a flat metal strip provided on one edge with an upwardly-extending elongated lug or flange, h, adapted to be locked between the arms g' of a section similar to the section f, already described, and on the other edge with the arms h', terminating in the oppositely-extending ends h'', adapted to engage the lugs g on the section f, the section f' being formed of a single piece of metal.

The form of link particularly described above is found to be well adapted to the purpose, and is easily and cheaply made; but I do not wish to limit myself to this particular form, as I may find it expedient to use links of different forms in the construction of different-sized combs.

The outside edges of the two end plates are provided with upwardly-extending ears K and k. The ear K is provided with a perforation, l, through which the operating-rod L passes and in which the rod is allowed a sliding motion, and the ear k is provided with a perforation, l', or other suitable device for securing the end of the operating-rod L rigidly to the ear.

To the inside surface of the ear K the thumb-plate k' is firmly secured, and extends upward far enough to conveniently receive the thumb, and then is bent downward near the outside surface of the ear K, and partially embraces

the operating-rod L. The operating-rod L is provided with a button, m, on its end to receive the pressure of the finger, and with a notch, n, formed transversely in its under portion a suitable distance from the button m. The rod L is further provided with a spiral spring, o, located between and rigidly secured at its opposite ends to the ears K k, which causes the plates D to automatically come together, or to a closed position. A spring-pressed dog, p, is secured transversely beneath the operating-rod L, between the thumb-plate k' and button m, and is adapted to engage the notch n and the bent-down portion of the thumb-plate k' at the same time, and thereby holds the plates D the required distances apart.

The comb represented in Fig. 1 is one of two similar combs adapted for use on a web of thirty-six stitches—eighteen front and eighteen back—and is used as follows: First, they open the plates D by pressing the thumb against the inner side of thumb-plate k' and finger against the button m until the dog p engages the rod and thumb-plate, and thereby holds the comb open. Then pick up all the stitches on the front, excepting one end stitch and every third one therefrom—that is, omit the stitches corresponding to the spaces between the groups of points. Next carry the comb the distance of one point to the right or left, as the case may be, and take up the remaining stitches. The comb is now closed by pressing down upon the dog p, which releases the dog from the rod and from the thumb-plate k' and permits the spring to draw the plates D together. The twelve points will now have the eighteen stitches on them, there being two stitches on every other point. This same process being carried out with respect to the eighteen back stitches, the entire thirty-six stitches will be placed on twenty-four points, and the double stitches will be evenly distributed throughout the entire circuit of the fabric. The stitches may now be put back on the needles and the knitting continued.

If it be desired to narrow more rapidly, the plates would be provided with but one point each, and the process above described would then double every stitch, reducing the thirty-six to eighteen.

The number of points on a single plate determines the rate of narrowing—for example, three points on each plate would reduce the number of stitches one-fourth; but in every case the narrowing will be evenly distributed throughout the entire circuit of the web, so

that the web will be brought to a natural apex seamless and without blocking.

Combs of different sizes are constructed to suit the different-sized webs, in order to narrow the whole front or back at once, and thereby save time and trouble.

My improved narrowing-comb is constructed with particular reference to use in connection with the Lamb knitting-machine, in which 65 latch-needles are employed.

It is evident that many slight changes may be made in the form and construction of the several parts without departing from the spirit and scope of my invention; hence I do not wish 70 to limit myself strictly to the construction herein set forth; but,

Having fully described my invention, what I claim as new, and desire to secure by Letters Patent, is—

1. The combination, with a bar, a series of sliding plates mounted on said bar, each plate being provided with one or more points, and links connecting the sliding plates, of a rod secured to one of the end plates, the other end 80 plate being provided with a thumb-piece, means for locking the sliding plates in open position, and a spring connecting both end plates and operating substantially as set forth.

2. The combination, with a bar, a series of 85 sliding plates mounted on said bar, and links connecting the several plates, of a thumb-piece formed on one of the end plates, a rod secured to the other end plate and passing through said thumb-piece and provided with a notch, 90 a spiral spring encircling said bar and secured to the end plates, and a dog for engaging the thumb-piece and rod, substantially as and for the purpose set forth.

3. The combination, with a bar, a series of 95 sliding plates each having one or more points, one of the outside or end plates of said series being provided with a thumb-piece and the other outside or end plate being provided with a rod, a spring connecting said outside or end 100 plates, and a dog for holding the plates in open adjustment, of the sheet-metal support bent to form a guard for the narrowing mechanism, substantially as set forth.

In testimony whereof I have signed this 105 specification in the presence of two subscribing witnesses.

ALFRED JAMES WAINMAN.
